UNITED STATES PATENT OFFICE.

HARRY W. HILL, OF CLEVELAND, OHIO.

DESIGN FOR A CLUTCH-FRAME.

SPECIFICATION forming part of Design No. 21,767, dated August 9, 1892.

Application filed June 4, 1892. Serial No. 435,564. Term of patent 14 years.

To all whom it may concern:

Be it known that I, HARRY W. HILL, a citizen of the United States, residing at Cleveland, in the county of Cuyahoga and State of Ohio, have invented and produced a new and original Design for Clutch-Frames, of which the following is a specification, reference being had to the accompanying drawings, in which—

- o Figure 1 is an elevation showing the outside of the clutch-frame. Fig. 2 is a sectional view in the plane indicated by line 2 2; and Fig. 3 is a sectional view in the plane indicated by line 3 3, these three views being deemed necessary to fully illustrate my design.

My newly-designed clutch-frame has a hub *a*, and arms *b*, which radiate from said hub.

The new and original features of my design are found in the shape of the arms *b*. Each of these arms is narrowest at or substantially at its outer end. The sides of each arm spread

apart gradually at first, and then, with increasing rapidity until near the hub, the sides of each arm are curving rapidly away from each other. Each side of each arm meets and unites with the proximate side of the adjacent arm in a broad graceful curve, substantially as shown.

The part of the frame formed by the arms above described is U-shaped in cross-section, as is clearly shown in Figs. 2 and 3, and the outside of the frame—that is, the side which will be seen when the frame is in use, and which is shown in Fig. 1—shows nothing but convex-curved surfaces.

35

What I claim is—

The design for a clutch-frame, as herein shown and described.

HARRY W. HILL.
